UNITED STATES PATENT OFFICE.

WILLIAM S. FULLERTON, OF ST. PAUL, MINNESOTA.

X-RAY APPARATUS.

981,256.

Specification of Letters Patent. Patented Jan. 10, 1911.

Application filed May 25, 1908. Serial No. 434,885.

To all whom it may concern:

Be it known that I, WILLIAM S. FULLERTON, a citizen of the United States, residing at St. Paul, in the county of Ramsey and 5 State of Minnesota, have invented a new and useful X-Ray Apparatus, of which the following is a specification.

My invention relates to X-ray apparatus. It has for its object a machine of convenient construction for use in X-ray photography as applied to the diagnosis of abnormal conditions in patients, and particularly to the adjustment of the X-ray apparatus to the patient without inconvenience 10 to the latter while a stereoscopic photograph is secured. It facilitates quick and comfortable adjustment to the patient's body, and permits the correct stereoscopic alinement of the tube on each side of the central 15 vertical line.

In the drawing Figure 1 is a side elevation of my machine, Fig. 2 is a front elevation of the same, with the base cut away. Fig. 3 is a detail showing the tube-holder 20 and shield, stereoscopically adjusted on either side of a central vertical line. Fig. 4 is a detail cross section of Fig. 2 taken on the line $x-x$.

The tube-holder 1, shield 2, and diaphragm 30 3, are carried on an arm 4, which is attached to a head 5, adapted to move vertically upon a tubular standard 6. The head slides freely upon the standard, and is counterpoised by means of the weight 7, connected 35 by the cords 8, with the head 5. Said cords pass freely over the pulleys 9. The compression lever 10 is bifurcated at its inner end, the bifurcations being united at their extremities to form the bow 10' which is 40 pivoted upon the head by means of the pintles 11. A link 12 connects the bow of the compression lever with an offset 13 provided upon the ring 14, which is snugly but movably fitted upon the standard 6. The ring 45 14 thus serves as a sliding fulcrum, which, when force is applied to the handle of the lever 10, cramps on the standard 6 and affords successive purchase points. It will be obvious that a vertical manipulation of the 50 handle of the lever will thus permit a step by step lowering of the head upon the standard, and a like depression of the tube-holder and other parts carried by the arm 4.

The frame 15, adapted to carry the tube, 55 shield and diaphragm, is suspended from the arm 4 by means of the lock rings 16, to per-

mit a rotary motion around the arm, by which the tube may be directed to any position on either side of the arm, ranging from the vertical to the horizontal, and this lock 60 ring 16 is retained in the desired position by the clamps 17. By loosening the clamps, it is also obvious that the tube, shield and diaphragm may be moved horizontally upon the arm 4, either toward or away from the 65 standard. Thus the frame 15, and the X-ray tube which it carries, may be moved, and secured against movement, both horizontally and rotatably upon the arm.

The frame 15 is provided with the guide 70 arc 18, upon which the casing 19 is adjusted to slide to the right or left, as distinctly shown in Fig. 3. This movement upon the arc is made after the vertical and horizontal adjustment of the light to the patient's body 75 for the purpose of securing two photographic exposures for the pictures to be used in a stereoscopic reproduction, as will be readily understood by those skilled in the art. The casing 19 is bolted to the rods 20 80 which carry the tube, shield and diaphragm. The lock screw 21 is provided for the purpose of securing the tube at the desired angle upon the arc. This arrangement permits the correct stereoscopic adjustment of 85 the tube on each side of a central vertical line, the anode of the tube maintaining the same relation to the photographic plate on either side.

The standard 6 is supported by the base 90 22, mounted upon ball bearing casters 23, to facilitate moving the entire instrument so that it may be quickly and comfortably adjusted to the patient's body as he lies on an ordinary lounge or bed, instead of requiring him to be lifted and placed in the apparatus, as is the case with other devices for 95 similar purposes.

It will thus be apparent that my invention possesses great mobility of adjustment; that 100 the entire instrument may be conveniently placed in position for use, and that the diaphragm may then be applied to the organ under inspection, by horizontal, vertical and radial adjustment so as to secure the best 105 results in X-ray photography.

Having described my invention, what I 110 claim as new and desire to protect by Letters Patent is:

1. In a device of the class described, a support for an X-ray tube comprising a stand- 110 ard and arm movable vertically thereon,

an arc carried by the arm, a sliding member supported by the arc and adapted to move radially on both sides of a vertical line passing through the center of the arc, and a 5 tube holder suspended from the sliding member.

2. In a device of the class described, a standard provided with a base, an arm and ring both slidably mounted upon the standard, a fulcrum supported by the ring, a lever having a link connection between the ring and fulcrum, an arc suspended from the arm and a tube holder suspended from the arc by means adapted to slide radially 15 thereon.

3. In a device of the class described, the combination of a tubular standard, a head slidably mounted thereon and counterpoised by means of a weight in the standard, a 20 lever pivoted upon the head and provided with a sliding fulcrum upon the standard, a horizontal arm carried by the head, a tube-holder and shield suspended from said arm, and means for moving and adjusting 25 the tube and shield radially and horizontally upon the arm, all for the purposes specified.

4. A device of the class described, comprising in combination a tube-holder, a frame extending in the form of an arc an 30 equal distance on each side of its vertical center, a hanger for the tube-holder adapted to move radially in the frame, a standard provided with a base, and means for supporting and moving the frame upon the 35 standard.

5. In a device of the class described, the

combination of a tubular standard, a head slidably mounted thereon, a counter-weight for the head, within the standard, a horizontal arm carried by the head, a tube- 40 holder and shield suspended from said arm, a lever pivoted upon the head, and a sliding ring upon the standard, connected with the lever and adapted to act as a fulcrum therefor.

6. In a device of the class described, the combination of a tubular standard, a head slidably mounted thereon, a counter-weight for the head, a tube-holder, means carried by the head for supporting the tube-holder, 50 a lever pivoted upon the head, and a sliding ring, upon the standard, connected with the lever, said ring being provided with an offset adapted to support a fulcrum for said lever.

7. A device of the class described, comprising in combination an X-ray tube, a tube-holder, a frame to support the same, an arm slidably mounted upon a standard, said frame being suspended from the arm, and means for moving the tube-holder in an arc, whereby the anode of the tube will maintain the same focus on each side of a central vertical line.

In testimony whereof I have signed my 65 name to this specification in the presence of two subscribing witnesses.

WILLIAM S. FULLERTON.
